MODULATION CIRCUIT FOR RETARDING FIELD GENERATORS

Hans Erich Hollmann, Berlin, Germany, assignor to Telefunken Gesellschaft für Drahtlose Telegraphie m. b. H., Berlin, Germany, a corporation of Germany

Application October 23, 1934, Serial No. 749,535
In Germany November 3, 1933

5 Claims. (Cl. 179—171)

It is known, in the prior art, that a generator connected in a Barkhausen-Kurz type of retarding-field circuit arrangement is modulable with relatively low alternating voltages and that the modulator potential e_m is superposed upon the retarding electrode potential E_b . While this method insures satisfactory modulation, it nevertheless involves the drawback that the modulating voltage works upon the internal retarding resistance 5 of the retarding field generator; in other words, upon the resistance acting between the cathode and the retarding field electrode. Since the latter resistance amounts to about 1000 ohms, this means a severe load for the source of the modulation voltage which, in the majority of cases, 10 consists of a transformer. In other words, although the voltages are inherently low, a considerable amount of modulation power must be provided.

This drawback is obviated entirely by the present invention. By the mere adoption of certain means and ways in the circuit organization, perfectly non-dissipative modulation of a retarding field generator is obtainable. The invention is based upon the fact that the oscillator tube 15 of a retarding field generator operates inside the saturation region, so that the total electron emission current $i_s = i_b + i_g$, distributed over the retarding field electrode and the grid, is constant. Consequently, in the state of oscillation, the retarding field characteristic $i_b = f(e_b)$, having an inverted image pattern, is transferred to the grid end in the very same manner as in the static characteristics of the retarding field tube. For instance, Fig. 1 shows the two statically plotted 20 current characteristics of an oscillating retarding field transmitter, i_b and i_g being observed as a function of the biasing retarding field voltage e_b .

According to this invention, the modulator voltage e_m is impressed not only upon the retarding field electrode, but, at the same time, also upon the grid. This means that operation takes place not only upon the retarding field characteristic $i_b = f(e_b)$, but, at the same time, also on the grid current characteristic $i_g = f(e_b)$. In this case i_b and i_g become added, resulting in the constant saturation current i_s , and the modulation voltage e_m , as a consequence, works upon the pure saturation resistance of the tube.

Fig. 1 shows curves explanatory of the component currents forming the total emission current. Figs. 2 and 3 show, schematically, two embodiments of the invention.

A circuit organization adapted to carry the basic idea of the invention into practice is illustrated in Fig. 2. Referring to the same, R de-

notes the retarding field tube which excites a Lecher wire system L united with the grid and the anode in well-known manner. M denotes the modulation transformer whose winding S_1 , as above pointed out, is included in the lead brought to the retarding field electrode so that a pure alternating voltage e_m becomes superposed upon the biasing voltage E_b of the retarding field electrode. In order that the modulation potential e_m , pursuant to the idea underlying this invention, 5 may also be fed to the grid, a second secondary winding S_2 of the modulation transformer may be included in the grid lead. Transfer of current for the modulation frequency may then be equalized and maintained constant by virtue of the 10 mutual inductance of the two windings S_1 and S_2 , 15 without any action being brought upon the primary winding.

Another circuit scheme is shown in Fig. 3, in which the modulation potential e_m is imparted to 20 the grid by way of a suitable condenser C and is prevented from leaking or draining away to the grid voltage source by the aid of the choke coil D contained in the grid lead. In this circuit arrangement the transfer of current is equalized 25 between grid and retarding field electrode by way of C, and for this reason the bridging condenser must be chosen so large that it will still constitute a short-circuit even for the lowest modulation frequency. Hence, in audio frequency modulation 30 a condenser of a few microfarads will be required, whereas for radio frequency modulation, say with one intermediate carrier frequency, the capacity of the turning bridge piece B will generally be sufficient. In this instance, all that will 35 be necessary is the connection of the choke-coil D.

What is claimed is:

1. An oscillation generator comprising an electron discharge device having an anode, cathode and a grid, means for supplying a positive potential to said grid and a less positive potential to said anode relative to said cathode, whereby there is obtained pendulum motion of electrons about said grid, and means for supplying modulating potentials co-phasally to said anode and 40 grid, the last said means comprising means for causing a constant saturation electron flow from said cathode.

2. In a modulation circuit for a retarding field type generator, an electron discharge tube having a cathode, an anode and a grid, means for impressing a highly positive charge on said grid relative to the charges on said cathode and said anode respectively, means for impressing simultaneously upon said grid and upon said anode, 45 50 55

respectively, modulation voltages which are co-phasal and additive in their effect, and means for maintaining a constant saturation electron flow from said cathode.

5. An oscillation generator comprising an electron discharge tube having a plate, a cathode and a grid, means for rendering the charge on said grid highly positive with respect to said cathode, means for maintaining a relatively small difference of direct current potential between the cathode and the plate, means for producing a constant saturation electron flow from said cathode, and means for impressing modulation voltages co-phasally upon said grid and upon said plate while facilitating the operation of the next previously mentioned means.

10. 4. A generator in accordance with claim 3 and having electrostatic coupling means between the grid and the plate for the transfer of modulating potentials to said grid, said coupling means having a low impedance to the band of frequencies of said modulating potentials.

15. 5. An oscillation generator comprising an electron discharge tube having a cathode, a grid and a retarding electrode, means for maintaining a highly positive charge on said grid with respect to said cathode, means for maintaining a relatively small difference of direct current potential between the cathode and the retarding electrode, a transformer having a primary winding upon which modulation potentials may be impressed, and two secondary windings, one of said secondary windings being in circuit between the cathode and the grid and the other of said secondary windings being in circuit between the cathode and the retarding electrode, and a capacitor inter-coupling the grid and the retarding electrode, 20 said transformer in combination with said capacitor constituting means for maintaining a constant amplitude of electronic emission from said cathode while impressing said modulation potentials co-phasally upon the electrodes of said tube.
